W. T. DONNELLY,
TENSION SCARF FOR TIMBERS.
APPLICATION FILED AUG. 31, 1918.

1,413,395.

Patented Apr. 18, 1922.

UNITED STATES PATENT OFFICE.

WILLIAM T. DONNELLY, OF BROOKLYN, NEW YORK.

TENSION SCARF FOR TIMBERS.

1,413,395.

Specification of Letters Patent. Patented Apr. 18, 1922.

Application filed August 31, 1918. Serial No. 252,145.

To all whom it may concern:

Be it known that I, WILLIAM T. DONNELLY, a citizen of the United States, and a resident of Brooklyn, in the county of Kings and State of New York, have invented certain new and useful Improvements in Tension Scarfs or Timbers, of which the following is a specification.

The invention relates to a joint for timbers, more particularly as used in the construction of wooden ships, floating dry docks and other structures employing large and long timbers which are usually exceedingly difficult to provide. It has for its object to provide a fabricated timber scarfing for joining the ends of lumber, whereby said lumber will be more efficiently utilized, and the largest possible percentage of strength thereof secured at the joint portion.

A further object of the invention consists in the provision for increasing the tensile strength of the splice through the compression of the timber ends.

The nature of the invention will be best understood when described in connection with the accompanying drawings, in which—

Fig. 1 is a detached view, illustrating the ends of two pieces of timber shaped in accordance with the invention.

Fig. 2 is a side elevation of two beams united in accordance with the present invention; and Fig. 3 is a plan thereof.

Similar characters of reference designate corresponding parts throughout the several views.

Referring to the drawings, 10 and 11 designate two timbers which it is desired to unite, and whose ends are formed in manner hereinafter set forth, substantially as shown in Fig. 1 of the drawings, the two ends being duplicates of each other but applied in reverse direction, as indicated. To provide the increased tensile strength, as well as strength against lateral stress, the ends of each length of timber to be united are provided with a plurality of tongues, for example 12 and 13, and 12' and 13', as indicated in Fig. 1. The two tongues enclose an inwardly tapering cutaway portion 14, and the outer side of tongue 13 is also cut away to provide a space 15 with which the tongue 13' of the oppositely-directed timber 11 is designed to register, the tongues 12' and 13' registering with the spaces 14 and 15 of the timber 10, the tongues of a set being upon

opposite sides of the median plane of the timber. Conversely, the tongues 12 and 13 register with the spaces 14' and 15' of member 11. The same form a snug fit between the ends and are of increasing taper inwardly; and by multiplying same as herein indicated, the frictional holding properties of the joint are correspondingly increased.

In order to secure an increased tensile strength of the joint portion, there is placed a compression upon the interlocking ends of the timbers 10 and 11, in that each is provided with a saw-cut 16 and 16' respectively, extending backwardly into the timbers from the inner end of the spaces 14 and 14', the slotting being effected immediately along one wall of the central scarf or median plane of the beam and beyond the extent of the scarfing. Bolts 20, which are preferably of the drive screw bolt type, as more fully set forth in U. S. Patent No. 1273588, granted me the 23rd day of July, 1918, are caused to extend through the various tongues, as well as through outer reenforcing planks 21 and 22 when these are employed, the same then extending over the joint and a certain distance beyond. These planks serve to maintain the effective section of the timbers, but may be dispensed with in some instances. It is to be noted, moreover, in connection with the use of the bolts 20, that by virtue of the multiplicities of splicings, the resistance to shear of said fastening members is greatly increased, in fact being, in the particular instance shown, three times greater than when employed in connection with a splice of the usual form. In addition, the length of the joint is reduced thereby, permitting of the use of shorter timbers. As these bolts are tightened, the compression of the timber ends through the saw-cut serves to firmly grip the ends of the splice. Additional drive or compression bolts are employed beyond the extent of the joint in order to gain full advantage of the compression, and a few spikes 23 may be driven into the timbers to further help to retain the planks thereto. It is to be noted, also, that the fastening members extending through the splice portion are in triple shear, as a result of doubling of the scarfing, although a further multiplying of the scarfing would not maintain the proportionate increase of the shear.

I claim:

1. A tension scarf for the coacting ends of two timbers having their abutting ends

110

provided with a plurality of similar tongues, said abutting ends being in reverse position with their tongues interlocking, and provided at the innermost portion of the scarf 5 with inwardly directed saw-cuts extending from the space between the tongues.

2. A tension scarf for the coacting ends of two timbers having their abutting ends provided with a plurality of similar tongues, 10 said abutting ends being in reverse position with their tongues interlocking, and provided at the innermost portion of the scarf with inwardly directed saw-cuts along the median plane extending from the space be- 15 tween the tongues.

3. A tension scarf for the coacting ends of two timbers having their abutting ends provided with a plurality of similar tongues, 20 said abutting ends being in reverse position with their tongues interlocking, and provided at the innermost portion of the scarf with inwardly directed saw-cuts extending from the space between the tongues, and bolts passing through both of the tongues and the joint thus formed. 25

Signed at New York, in the county of New York and State of New York, this 29th day of August, A. D. 1918.

WILLIAM T. DONNELLY.
